U.S. Appl. No. 29/221,972, Jordi Miro.

* cited by examiner

Primary Examiner—Sandra S. Snapp(74) *Attorney, Agent, or Firm*—Kilpatrick Stockton LLP(57) **CLAIM**

I claim the ornamental design for an air deodorizing packet, as shown and described.

DESCRIPTION

FIG. 1 is a front perspective view of an air deodorising packet comprising the present invention.

FIG. 2 is a rear perspective view of the air deodorising packet shown in FIG. 1.

FIG. 3 is a front elevational view of the air deodorising packet shown in FIG. 1 and FIG. 2.

FIG. 4 is a rear elevational view of the air deodorising packet shown in FIG. 1, FIG. 2, and FIG. 3.

FIG. 5 is a left side elevational view of the air deodorizing packet shown in FIG. 1, FIG. 2, FIG. 3 and FIG. 4.

FIG. 6 is a right side elevational view of the air deodorizing packet shown in FIG. 1, FIG. 2, FIG. 3, FIG. 4 and FIG. 5.

FIG. 7 is a top plan view of the air deodorizing packet shown in FIG. 1, FIG. 2, FIG. 3, FIG. 4, FIG. 5 and FIG. 6; and,

FIG. 8 is a bottom plan view of the air deodorizing packet shown in FIG. 1, FIG. 2, FIG. 3, FIG. 4, FIG. 5, FIG. 6 and FIG. 7.
